UNITED STATES PATENT OFFICE.

H. M. VIETS, OF CARLISLE, OHIO.

IMPROVEMENT IN MAKING CHEESE-HOOPS.

Specification forming part of Letters Patent No. 79,164, dated June 23, 1868.

To all whom it may concern:

Be it known that I, H. M. VIETS, of Carlisle, in the county of Lorain and State of Ohio, have invented certain new and useful Improvements in Cheese-Making Hoops; and I do hereby declare that the following is a full and complete description of the same, reference being had to the accompanying drawings, making a part of this specification, in which—

Figure 1 is a perspective view of the hoop; Figs. 2, 3, and 4, detached sections.

Like letters of reference refer to like parts in the several views.

Fig. 3 represents a hoop, which is constructed in two sections, A B, section A being fitted to the inside of B, so that B forms a wide hoop or band around the lower edge of A, and to which it is soldered or otherwise permanently secured. Fig. 2 also represents a hoop, and which is of the same diameter as section A. This hoop is also fitted to the inside of section B, so that when inserted in B its upper edge will meet the lower edge of section A, thereby making the inner surfaces of the two hoops flush, and horizontally closely fitting together.

In order for a proper understanding of the operation of this arrangement of hoops, I will briefly describe the ordinary process of pressing the curd into shape, which is done by throwing it into a deep cheese-hoop of the proper size, on which a follower is placed, which is then submitted to the press. When sufficiently pressed, it is taken from the hoop and covered with cloth, as follows: A strip of cloth equal in length to the circumference of the cheese, and of a width some inches more than its thickness, is drawn around and secured to the edge of the cheese. The edges of the cloth are then folded down upon the sides. The yet naked central part of the cheese is covered by a disk of cloth, cut to the proper size, and laid upon it, and to which it is made to adhere by pressure or otherwise.

This matter of covering or clothing the

cheese is a work of much time and labor, requiring no little skill in its proper performance, to avoid which is the purpose of the hoop above described, and which is used in the following manner: A piece of cloth of the proper size to cover the edge and one side of the cheese is laid upon the hoop C, and pressed down into and smoothly adjusted therein. The edge of the cloth is lapped down over the sides of the hoop, as shown in Fig. 1, in which a represents the cloth, and the dotted line a' the lower edge of the hoop. In this condition of the hoop and cloth the hoop A B is forced down over it, thereby binding the cloth between the two hoops. The curd is now put into the hoop on the cloth, which, as will be obvious, covers the bottom of the press-board. The follower, Fig. 4, is now put on, and the curd subjected to the press, in the ordinary way. This being done, the upper section of the hoop A B is removed with the follower, and the cheese taken out, the edge of which and side will be found covered with the cloth previously put into the hoop. The loose edge of the cloth is now folded down around upon the upper side of the cheese, and the central space is then covered by a disk of cloth, cut and fitted for that purpose, thus completing the clothing of the cheese immediately on its leaving the press.

The pressing and most of the clothing being done at one operation, saves largely in time and labor, as it is not necessary to handle the cheese in order to put on the last piece of the covering.

What I claim as my improvement, and desire to secure by Letters Patent, is

The hoop C, in combination with the hoop A B, in the manner as and for the purpose specified.

H. M. VIETS.
